UNITED STATES PATENT OFFICE.

JOHN J. DONOVAN, OF BOSTON, MASSACHUSETTS.

SEPARATOR-TRAP.

1,252,099.

Specification of Letters Patent.

Patented Jan. 1, 1918.

Application filed October 5, 1916. Serial No. 123,895.

To all whom it may concern:

Be it known that I, JOHN J. DONOVAN, a citizen of the United States, residing at Boston, in the county of Suffolk and State 5 of Massachusetts, have invented new and useful Improvements in Separator-Traps, of which the following is a specification.

The object of the present invention is to provide a separator trap for separating liquids of different specific gravities. The device as shown by the accompanying drawings is designed for installation in a drain pipe leading to a sewer. In garages that have floor drains to carry off the water that 10 is used for washing automobiles it frequently happens that gasoline and other light liquids that give off explosive vapor are spilled on the floor and are drained through the pipe that communicates with 15 the sewer, and if the explosive liquid is permitted to flow to the sewer it becomes vaporized in the latter and is likely to become ignited and to cause an explosion.

My present invention provides a separator trap that prevents light explosive liquids from passing to the sewer with the water that is drained from the floor. It also separates the lighter liquid from the water and causes the former to accumulate in a 20 separate chamber or receptacle. If an excessive volume of water, or water and lighter liquid, should flow into the trap at one time, the trap prevents the water from overflowing into the receptacle or chamber that is 25 intended exclusively for the lighter liquid, to the end that the lighter liquid may be removed from time to time from its receptacle as it accumulates therein, free from water and in a usable condition. My device acts 30 also as a safeguard against neglect to remove the lighter liquid from its receptacle, in that it closes the outlet to the sewer whenever the lighter liquid has accumulated to a predetermined level in the receptacle, 35 provided for that purpose. The result of closing communication between the trap and sewer is that no more liquid can pass through the trap, and the water that would under normal conditions be drained from 40 the floor to the sewer will have no outlet and will accumulate on the floor. In order, therefore, to reopen communication between the floor drain and the sewer it is necessary 45 to remove a substantial quantity of the lighter liquid from its receptacle. If the

outlet pipe forming communication between the separator and the sewer should become obstructed to an excessive degree by an accumulation of dirt, the normal condition of the separator would be restored by removing 60 such accumulation. A clean-out pipe is provided for that purpose. In no case, however, would an excessive accumulation of water in the separator result in overflow of water into the receptacle for the lighter liquid, for 65 the device is provided with a float valve arranged to close communication between the water compartment and the receptacle for the lighter liquid, regardless of what condition is responsible for an excessive accumulation of water in the water compartment. 70

Of the accompanying drawings, which illustrate one form in which the present invention may be embodied:

Figure 1 represents an elevation including the separator trap, a floor drain for conducting liquids thereto, an outlet pipe for conducting water from the separator to the sewer, a clean-out for the latter pipe, and an auxiliary receptacle for the lighter liquid 80 that is separated from the water. 75

Fig. 2 represents a vertical section, on a larger scale, of the separator from the same point of view as Fig. 1.

The same reference characters indicate the 85 same parts wherever they occur.

A floor surface is indicated at 10 in Fig. 1, and a drain pipe for the floor is indicated at 11. The casing of the separator is indicated at 12. The separator is divided by a partition wall 13 to provide a trap chamber 14 and a storage chamber 15 for the lighter liquid. Drain pipe 11 conducts the liquid into chamber 14. The outlet pipe that conducts the water to the sewer is indicated at 16, and has a trap portion 17 and a clean-out portion 18. The outlet pipe is in communication with the chamber 14 below the normal water level. Said water level is indicated by broken line $x-x$. An intermediate portion of pipe 11 is broken out, for the receiving end of said pipe need not be as close to the separator as shown by Fig. 1, but would, in the majority of cases, be more remote therefrom. If desired, a trap may be interposed 100 in pipe 11, between the receiving end of the latter and chamber 14, to accumulate dirt, but this would be an immaterial consideration as far as the present invention is concerned. 105

Casing 12 is provided with a removable cover formed in two sections, the latter being indicated at 19 and 20 respectively. The cover sections may be fastened to the casing 5 by any suitable means which, if the cover is to be flush with the surface of the floor as shown by Fig. 1, would preferably have provision for holding packing material as indicated at 21. The purpose of packing 10 material would be to prevent liquids from leaking directly into the chambers of the separator and to prevent vapor from leaking out. Chamber 14 is provided with a vent pipe 22, and chamber 15 is provided 15 with a vent pipe 23.

The receiving end 24 of the sewer pipe (Fig. 2) is formed to provide a valve seat and provided with a swinging valve 25. Said valve is mounted upon a pivot member 26, and closes in the direction of flow. This valve and likewise the other movable elements shown by Fig. 2 occupy the positions represented by solid lines when normal 20 conditions exist. Valve 25 remains open 25 excepting when the lighter liquid has accumulated to a predetermined level in chamber 15, and is closed automatically when the lighter liquid reaches such level, as will be understood after further description.

30 An elbow member 27 forms communication from chamber 14 to chamber 15, and is formed with an annular flange 28 through which the lighter liquid may flow. This flange is passed through a hole in partition 35 13 and is provided with a screw-thread to receive a clamping nut 29. The joint is made tight by a washer 30 of packing material.

The receiving end of elbow member 27 is 40 formed to provide a valve seat for a valve 31, said seat being indicated at 42. This valve has a vertical rectilinear movement toward and from its seat, and has a stem 32 that is guided by a spider 33. The valve 45 member is arranged directly upon the float element. The float and valve collectively are lighter than water but heavier than gasoline or other liquid of a similar nature. As shown by Fig. 2 this float is sustained by 50 the buoyancy of the water at level $x-x$, and even though a body of lighter liquid might rest on the water, the valve would not close the receiving end of member 27. The passageway through member 27 therefore 55 mains open, excepting as hereinafter explained, to enable lighter liquid to overflow from chamber 14 into chamber 15; but if the water in chamber 14 should rise to the level of valve seat 42 it would carry the valve 60 to said seat and thus close communication between the two chambers. Valve 41 is therefore the means of preventing water from entering member 27. Any lighter liquid that has not enough buoyancy to sustain 65 it would be free to flow into chamber 15

as long as the valve is separated from its seat. Line $y-y$ represents the level to which gasoline would have to rise to force the water level down to the top of mouth 24.

The description so far accounts for the 70 separation of the lighter liquid from the water and for preventing water from overflowing into chamber 15 in the event of an excessive accumulation of water in chamber 14. If an excessive accumulation of water 75 in chamber 14 were due to obstruction in the outlet pipe, such obstruction could be removed through clean-out 18, whereupon the water would flow through pipe 16 to the sewer until its level drops to line $x-x$. 80

I will now describe the means for automatically closing communication with the sewer when an excessive quantity of the lighter liquid has accumulated in chamber 15. Outlet valve 25 is normally sustained 85 in open position by rod 44. The upper end of this rod is connected to an oscillatory arm 45 by a pivot member 46. Arm 45 is affixed to a rockshaft 47, and the latter is provided with a second arm, indicated at 48. Arms 90 45 and 48 extend substantially in opposite directions from the axis of the rockshaft, so that the outer end of one will rise as the outer end of the other moves downwardly, and vice versa. The upper end of a link 49 95 is connected to arm 48 by a pivot member 50, and the lower end of said rod is connected to a float arm 39 by a suitable connection including a pivot member 51. Arm 39 carries a float 40, and is arranged upon 100 a fulcrum pin 38. The combined weight of the elements in chamber 15, that are connected to rockshaft 47, is greater than the combined weight of the elements in chamber 14, that are connected to said rockshaft, and 105 consequently valve 25 will be sustained in open position as long as the level of liquid in chamber 15 is below the level indicated by broken line $a-a$, although as float 40 rises valve 25 will move toward its seat. On 110 the other hand, as the liquid is removed from chamber 15, float 40 will descend and raise valve 25.

Rockshaft 47 has its bearing in a sleeve 115 53, and the latter is arranged to extend through a hole in partition 13 and is clamped to said partition by a clamping nut 54. The sleeve is counterbored for the reception of packing material 55, and is provided with a screw-cap 56 to confine the packing material 120 and to furnish a bearing for one end of the rockshaft. This bearing support for the rockshaft prevents liquid from leaking into chamber 15 from chamber 14 in the event that the latter chamber becomes filled with liquid through a stoppage of the outlet pipe, either by an accumulation of dirt or by the closing of valve 25. Inasmuch as the pressure of liquid in chamber 14 would never be appreciable, packing material 55 would 125 130

not have to be compressed to a degree that would materially resist motion of the rock-shaft.

I have shown a pump 57 for removing the liquid from chamber 15. The handle of the pump is indicated at 58. In the present instance the barrel of the pump extends through a hole in cover section 20 and has screw connection with the latter. The upper 10 or outer end of the pump is provided with a nipple 59 adapted to receive a coupling device of a hose, so that the liquid may be pumped into a portable receptacle. The capacity of chamber 15 is optional, but for the 15 sake of economy in the manufacture of the casing 12 the chamber 15 would preferably be only so large as to accommodate the necessary operating elements. Hence, if it were desirable, in any case, to store a greater 20 quantity of the lighter liquid than the chamber 15 would accommodate, an auxiliary receptacle could be arranged at substantially the same level as the casing 12 and located at any convenient distance from 25 it, and connected to chamber 15 by a pipe. I have therefore indicated an auxiliary receptacle at 60 in Fig. 1 and have included a pipe 61 for conducting liquid from chamber 15 to the auxiliary receptacle. The lines 30 that represent the pipe 61 are broken to indicate that the receptacle 60 may be at a relatively great distance from casing 12 instead of being located in the close relation shown. Receptacle 60 would be arranged at 35 a level that would enable the liquid therein to flow back to chamber 15 as well as to enable the liquid to flow in the opposite direction, so that such liquid could be pumped out from both the chamber and auxiliary receptacle by pump 57. Receptacle 60 is provided 40 with a vent pipe 62.

In order to insure the desired operation of the device when it is first put to use, it would be desirable to let enough water flow 45 into it to fill it to the level indicated by line $x-x$. If a large quantity of gasoline or other light liquid should flow into the device before any water has entered, the lighter liquid would pass through outlet 50 pipe 16 to the sewer, but the initial presence of water would sustain the lighter liquid so that the latter would flow into the chamber 15 provided for that purpose. Once the 55 requisite quantity of water has been introduced into the device the desired separation of liquids will follow as a natural consequence.

My device becomes incapable of acting as

a drain whenever an excessive quantity of water accumulates in the trap chamber 14, 60 regardless of what causes such excessive accumulation, and thus puts the user under the necessity of removing the lighter liquid if that be the cause of stoppage, or of removing an accumulation of dirt from the 65 outlet pipe if that be the cause of stoppage.

I claim:

1. A separator trap comprising a trap chamber having an inlet, an outlet for water and an outlet for liquid lighter than water, 70 the latter one of said outlets being above the level of the highest portion of the water outlet, and a float valve responsive to the buoyancy of water in said chamber but non-responsive to a liquid lighter than water, said 75 valve being arranged to close the upper one of said outlets when the water in said chamber is above said level but below the upper outlet.

2. A separator trap comprising a trap 80 chamber having an inlet and two outlets, said outlets being respectively above and below the normal water level of said chamber, a storage chamber arranged to store whatever liquid overflows said trap chamber 85 through the upper one of said outlets, a valve arranged to control the escape of liquid through the lower one of said outlets, a float arranged in said storage chamber, and means arranged to transmit motion 90 from said float to said valve to close the latter when liquid accumulates to a predetermined level in said storage chamber.

3. A separator trap comprising a trap chamber having an inlet and two outlets, 95 said outlets being respectively above and below the normal water level of said chamber, a storage chamber arranged to store whatever liquid overflows said trap chamber through the upper one of said outlets, a valve arranged to control the escape of liquid through the lower one of said outlets, a float arranged in said storage chamber, means arranged to transmit motion from 100 said float to said valve to close the latter 105 when liquid accumulates to a predetermined level in said storage chamber, and a float valve responsive to the buoyancy of water in said trap chamber and arranged to close the upper one of said outlets when the water 110 level in said trap chamber is above said normal level and below the latter said outlet.

In testimony whereof I have affixed my signature.

JOHN J. DONOVAN.
